United States Patent Office

Des. 206,162
Patented Nov. 8, 1966

206,162

HEARING AID

Robert L. Geib, Wayzata, and Richard T. Martin, Minneapolis, Minn., assignors to Dahlberg Electronics Inc., Minneapolis, Minn., a corporation of Minnesota

Filed Sept. 23, 1965, Ser. No. 87,126

Term of patent 14 years

(Cl. D26—14)

FIG. 1 is a side elevational view of a hearing aid showing our new design, the opposite side being substantially a mirror image thereof;

FIG. 2 is a top plan view thereof;

FIG. 3 is a bottom plan view thereof;

FIG. 4 is an end elevational view thereof as seen from right to left of FIG. 1; and

FIG. 5 is an opposite end view thereof.

We claim:

The ornamental design for a hearing aid, as shown and described.
